ROTATABLE CHRISTMAS ORNAMENT

Werner A. Heinzel, Greenwood, Del.

Application April 20, 1953, Serial No. 24,578

Term of patent 14 years

(Cl. D29—1)

To all whom it may concern:

Be it known that I, Werner A. Heinzel, a citizen of Germany, residing at Greenwood, Delaware, have invented a new, original, and ornamental Design for a Rotatable Christmas Ornament, of which the following is a specification, reference being had to the accompanying drawing, forming a part thereof.

In the drawings:

Fig. 1 is a side elevational view of a rotatable Christmas ornament, showing my new design;

Fig. 2 is a sectional view thereof, taken along the line 2—2 of Fig. 1, with the candles removed for convenience in illustration only; and

Fig. 3 is a top plan view thereof.

I claim:

The ornamental design for a rotatable Christmas ornament, as shown and described.

WERNER A. HEINZEL.
